HAND GUARD

Earle M. Harvey, Springfield, Mass., assignor to
the United States of America as represented by
the Secretary of War

Application July 7, 1945, Serial No. 603,730

9 Claims. (Cl. 42—75)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to improvements in firearms and is directed more particularly to the provision of a novel handguard assembly especially adapted for use in connection with gas-operated firearms.

It has been usual in the prior art to provide wood or plastic handguards in the form of a channel having a generally U-shaped cross-section. For example, the handguard of the U. S. rifle, cal. .30 M1 has its lower side ordinarily open exposing the gas cylinder and operating rod, which are necessarily composed of metal and tend to heat up upon firing of the weapon, with the result that the hands of the firer are frequently burned or, at least, the convenient and efficient firing of the weapon is interfered with.

In the case of rifles or weapons of other types where the construction is such that there is no objectionable exposure of metal, there has always still been the objection that the wood, of which handguards are commonly formed, becomes charred and after a reasonable amount of use, naturally wears away. Consequently, the guard becomes loosely associated with the firearm.

Accordingly, it is a principal object of this invention to provide a handguard assembly which overcomes the disadvantages of both danger to the firer and objectionable charring of the wood. This is accomplished by providing a handguard body member which is of unitary construction and which entirely surrounds and protects the barrel and operating rod assemblies while being spaced from said barrel and assemblies except at its ends. That is to say, the body member is so formed as to have what may be referred to as a split longitudinal bore, the upper portion of said bore being adapted to receive the barrel parts of the weapon and the lower part thereof being arranged to receive the gas cylinder, gas cylinder bracket, etc. The body member has its inner surface spaced from the contiguous outer surfaces of said barrel and gas cylinder, whereby to provide a heat-insulating air space therebetween.

As will be presently disclosed, the construction of the handguard assembly of this invention also includes a metallic front band or stock ferrule of novel design. This both reinforces the handguard body and protects it against any possible injury through forced contact or other engagement with other metal parts of the weapon while

2

at the same time acting positively to maintain the handguard body out of contact with the barrel, gas cylinder, etc., as aforesaid.

The specific nature of the invention as well as other objects and advantages thereof will clearly appear from a description of a preferred embodiment as shown in the accompanying drawings in which:

Fig. 1 is an elevational view of the blank from which a front ferrule embodying this invention is formed.

Fig. 2 is an elevational view of a finished front ferrule.

Fig. 3 is a partial longitudinal sectional view on line 3—3 of Fig. 7 showing the mode of securing the front ferrule to the wood handguard.

Fig. 4 is a part elevational view of a rear handguard ferrule constructed in accordance with this invention.

Fig. 5 is a sectional view of Fig. 4 taken along the plane 5—5.

Fig. 6 is a rear elevational view of the rear handguard ferrule.

Fig. 7 is a longitudinal sectional view of the barrel portion of a firearm, showing the handguard and front and rear ferrules in assembled relation.

Fig. 8 is a sectional view of Fig. 7 taken on the plane 8—8.

The body of the handguard is indicated generally by the numeral 2 and its outer configuration is substantially that of an oval. The body 2 is provided with a longitudinal bore 4 which extends entirely therethrough and in cross-section is approximately the shape of a pair of overlapping circles.

That is to say, the thickness of its opposite mid-side portions is relatively greater than its upper and lower portions or in other words there are longitudinally-extending and oppositely-disposed ribs 10 on the inner sides of the bore. While such ribs serve to strengthen the body and obviate the possibility of its collapsing, as will be appreciated, their principal function is to form upper and lower bore portions 12 and 14 which, while connected, are nevertheless spaced from one another.

The ribs 10 are interiorly cut away just rearwardly of the said forward end face of the body so as to provide opposed slots 42. It is to be understood that there may be just one of such slots 42.

The upper bore 12 is arranged to receive the barrel 10 of the weapon, while the lower portion

14 is for receiving the gas cylinder 80 and associated parts. In each case the transverse dimensions of the bores is such as to provide a substantial clearance between the body, on the one hand, and the barrel, gas cylinder, etc., on the other hand. The forward outer end portion of the body member is profiled so as to provide a reduced neck part 17 while its rear face 18 is substantially flat as shown.

In Fig. 1, there is shown a metal blank from which the front stock ferrule member 20 is preferably formed and said blank consists essentially of an oval-shaped piece of flat, sheet-metal stock. This piece is punched, or cut out, to have a pair of spaced and more or less circular openings 22 to accommodate barrel 70 and gas cylinder 80 that are snugly fitted therein, one opening being disposed at each end of said oval or blank.

The said openings 22 in the blank are separated by a part 24 which extends transversely of the narrower width of the oval and preferably has its opposite marginal edges substantially parallel and straight, with the result that the adjacent sides of openings 22 are flattened. The transversely-extending member 24 is also provided with a cross-wise cut 26 which extends entirely therethrough on a line at right angles to the said straight edges thereof thus forming two free end portions 25.

Therefore, the said blank 20 is such that it may be pressed into suitable shape, as by a die, so that as shown in Figs. 2 and 3, the outer marginal edge portions of said blank may be turned at right angles to form a rim-like portion 30 snugly fitting reduced neck 17. The inner marginal edge portions are turned at right angles to form a rim-like portion 32 to snugly embrace the bores at the forward end face of the handguard body 2 and to be substantially flush and coplanar with its exterior end surface.

The cut 26 through the transverse member 24 of the ferrule permits the further bending of the inner and adjacent or free end portions or wings 25 of the transverse member so that the same may be bent inwardly into engagement with the slots 42 in the ribs 10 of the handguard so as to firmly secure the ferrule to the guard proper and effect a rigid assembly.

It is also desirable that a rear band 50 or ferrule be provided and, as shown in Fig. 4, this likewise has the general outer configuration of an oval. Band 50 is arranged to be secured to the barrel 70 of the weapon by a pin 65 inserted through a transverse hole 60 and it includes a forwardly-protruding, cylindrically shaped upper portion 52 defining an upper opening 54 through which the barrel 70 extends with a snug fit, and a lower and more or less horse-shoe shaped forwardly protruding lower portion 56 integral therewith defining an opening 58 through which the gas cylinder 80 extends. It will be noted that the diameter of opening 54 is less than the diameter of bore 12 in body 2, so that ferrule 50 coacts with ferrule 20, positively to locate body 2 in spaced relation with barrel 70. Since gas cylinder 80 is fixed to barrel 70 at its rear end by means not shown, body 2 is held out of contact with both barrel and gas cylinder, and a heat-insulating air space is provided that effectively prevents heating and charring of the body.

Thus the rear end portion of the handguard body member may be assembled in surrounding relation on the portions 52 and 56 defined by the rear ferrule.

This construction has the obvious advantage

of obviating the customary reducing of the thickness of the wall of the rear end portion of the guard in order to accommodate its association with the rear ferrule, which has always resulted in weakening of the guard at this point.

I claim:

1. A handguard assembly for a gas operated firearm having a barrel and gas cylinder adjacent thereto comprising in combination, a longitudinally-extending tubular member which has its outer surface substantially oval-shaped in cross-section and the general contour of its interior surface being that of a pair of overlapping circles so as to provide upper and lower bore portions which are separated by a relatively narrow longitudinally-extending channel, said upper bore portion being arranged to receive the barrel of the firearm and the lower bore portion being arranged to receive the gas cylinder of the firearm, and a ferrule member rigidly secured to the forward end portion of said tubular member and provided with an opening therethrough and parallel with the configuration of the opening through the tubular member said ferrule being adapted to snugly fit the barrel and gas cylinder, and having internal transverse dimensions less than the corresponding dimensions of said member, whereby to provide a heat-insulating air space between said body, on the one hand, and the barrel and gas cylinder, on the other hand.

2. A handguard assembly for a gas operated firearm having a barrel and a gas cylinder adjacent thereto comprising in combination, a longitudinally-extending tubular member which is substantially oval-shaped in cross-section and has an opening therethrough in the general configuration of two overlapping circles so as to provide upper and lower bore portions which are spaced apart although connected, the upper bore portion being arranged to receive the barrel of the firearm and the lower bore portion being arranged to receive the gas cylinder of the firearm, and a metallic ferrule member embracing and secured to the forward end portion of said tubular member said ferrule having an internal contour of lesser transverse dimensions than the corresponding dimensions of said tubular member, said internal contour being adapted to fit snugly about the barrel and gas cylinder, whereby to hold said body in spaced relation with the barrel and gas cylinder and provide a heat-insulating space therebetween.

3. A handguard assembly for a firearm comprising in combination, a unitary, substantially oval-shaped body member provided with a longitudinally-extending bore therethrough, said bore having a general configuration of two overlapping circles so as to form spaced communicating upper and lower bore portions and whereby the thickness of the wall of said body member intermediate said bore portions is greater than that of the rest of the wall, the outer surface of the forward end portion of the body member being externally profiled so that the thickness of the wall thereof is less than that of the rest of the wall and a metallic ferrule member secured to said forward profiled end portion of the body member and including a plate-like part disposed over the face of said forward end portion and an integral rim-like portion embracing the profiled part of the body member said ferrule member having an internal contour defined by two overlapping circles of lesser diameter than the diameters of the corresponding bores of said body

member, said ferrule being adapted to fit snugly about the barrel of a gun and its adjacent gas cylinder.

4. A handguard assembly for a gas-operated firearm having a barrel and a gas cylinder parallel and adjacent thereto, said handguard comprising a body member having a bore extending longitudinally therethrough, said bore having a cross section generally in the form of two overlapping circles, said circles being of greater diameter than the diameters of the barrel and gas cylinder, respectively, and a ferrule secured to the forward end of said handguard, said ferrule being constructed and arranged to fit snugly about the barrel and gas cylinder and thereby hold the handguard in spaced relation with the barrel and gas cylinder.

5. A handguard for a gas-operated firearm having a barrel and a gas cylinder adjacent and parallel thereto, a body member substantially elliptical in outer cross section and having a bore extending longitudinally therethrough, said bore having a cross section generally in the shape of a first pair of overlapping circles substantially larger than the barrel and gas cylinder, respectively, and having their centers separated substantially the same distance as the axes of the barrel and gas cylinder, said bore having oppositely and transversely disposed slots near the forward end thereof, and an open metallic ferrule secured to and about the forward end of said body member and having an inner opening defined by a second pair of overlapping circles of smaller diameter than said first pair, respectively, said ferrule being adapted to fit snugly about the barrel and gas cylinder, whereby to maintain said member in fixed spaced relation with the barrel and gas cylinder.

6. A handguard assembly for a firearm having a barrel and a generally cylindrical operating element in spaced parallel relation therewith, a body member having a longitudinally extending bore in the shape of two parallel overlapping cylinders, having their axes spaced the same distance as the barrel and element and of larger radii than the barrel and element, respectively, said bore having oppositely and transversely disposed slots near the forward end thereof, a first metallic ferrule embracing and secured to, the forward end of said member, a second metallic ferrule secured to and about the rear end of said member, both said ferrules having openings snugly fitting the barrel whereby to mount said member with its bore in radially spaced relation with the barrel and element.

7. A handguard as specified in claim 6, said first ferrule also snugly fitting about said element.

5 8. A handguard as in claim 6, the forward end of said member being externally reduced to form a shoulder, said ferrule snugly fitting said shoulder and extending over and about the surface of said end and having integral lugs extending from the inner periphery thereof, said lugs engaging within said slots of said member.

10 9. A handguard for a gas operated firearm having a barrel and a gas cylinder adjacent and parallel thereto, a body member substantially elliptical in outer cross section being reduced at the forward end to form a shoulder and having a bore extending longitudinally therethrough, said bore having a cross section generally in the shape of a first pair of overlapping circles substantially larger than the barrel and gas cylinder respectively and having their centers separated substantially the same distance as the axes of the barrel and gas cylinder, said bore having oppositely and transversely disposed slots near the forward end thereof, and an elliptically shaped ferrule being U-shaped in cross section to fit over said reduced forward end of said member thereby providing an inner opening defined by a second pair of overlapping circles of smaller diameter than said first pair respectively adapted to fit snugly about the barrel and gas cylinder thereby maintaining said member in fixed relationship with the barrel and gas cylinder, said ferrule having integral lugs extending from its inner periphery and into engagement with said slots of said member thereby securing said ferrule and handguard together.

30 35 EARLE M. HARVEY.
